UNITED STATES PATENT OFFICE

2,660,270

UNIT PARTITION WALL CONSTRUCTION

Edward M. Jenkins, Somerville, and Thomas L. Acken, Jr., New Brunswick, N. J., assignors to Johns-Manville Corporation, New York, N. Y., a corporation of New York

Application September 10, 1946, Serial No. 695,866

1 Claim. (Cl. 189—34)

1

The instant invention relates to wall or partition assemblies and particularly to units which may be prefabricated for the erection of laboratory walls and the like. In modern laboratory construction the trend is to multiple cell-type, space divisions with provision for rearrangement of the space as need may arise. In order to attain full advantage of this type of construction, complete flexibility is required, both with respect to the partitions and to the associated plumbing and service lines. The terms "plumbing" and "service lines" are used in accordance with conventional practice, the term "plumbing" applying to all of the piping required and the term "service lines" referring particularly to the incoming lines, namely the water, air, vacuum and gas lines, etc. A principal object of the instant invention is the provision of a system of laboratory wall construction in which both the wall and the plumbing are on a unit basis, providing complete flexibility and permitting rearrangement of the partitions and plumbing to meet particular requirements.

Another object of the invention is the provision of a wall or partition construction incorporating the plumbing within the interior of the wall, all plumbing as well as the partition itself being constructed on a similar unit basis to allow for rapid erection and rearrangement. Also the instant construction is one which provides ready accessibility to the service lines, even though they are completely concealed within the wall, whereby they may be originally installed with a minimum of labor and later removed, replaced or altered without reconstruction of, or injury to, the wall. The placing of the piping within the wall greatly improves the appearance and utility of the wall and has the further advantage of increasing the working space within the laboratory. In conventional practice the piping is hung on the exterior of the wall, the piping requiring approximately 7" of floor space. By incorporating the piping within the wall, additional working space of this width is obtained. In modern laboratory constructions of the type referred to above having multiple cell-type, space divisions, this saving, when multiplied by the number of laboratories involved, becomes of real importance.

A further object of the invention is the provision of a supporting structure for the piping within the wall space. A still further object is the provision of a stud having a section provided with notches or seats of a character to support piping, the seats opening into a face of the stud. In one embodiment of the invention the seats or notches are provided in a rigid supporting

2

stud core while in another embodiment a separate hanger including the notches or seats is incorporated in the stud construction.

A still further object of the invention is the provision of a panel arrangement whereby readily removable access panels are employed as a wall facing overlying the service lines.

The invention will be more fully understood and further objects and advantages will become apparent when reference is made to the following more detailed description of a preferred embodiment and to the accompanying drawings in which:

Fig. 1 is an elevational view, with portions broken away for clearness of illustration, of a wall or partition construction in accordance with the instant invention;

Fig. 2 is a sectional view, taken on the line 2—2 of Fig. 1;

Fig. 3 is a sectional view, on an enlarged scale, taken on the line 3—3 of Fig. 1;

Fig. 4 is a sectional view, on an enlarged scale, taken on the line 4—4 of Fig. 1;

Fig. 5 is a perspective view, on an enlarged scale, of a section of studding employed in the wall construction;

Fig. 6 is a sectional view, on an enlarged scale, taken on the line 6—6 of Fig. 1;

Fig. 7 is a sectional view, on an enlarged scale, taken on the line 7—7 of Fig. 1;

Fig. 8 is a view similar to Fig. 5 showing a modified form of studding;

Fig. 9 is a side elevational view of the studding of Fig. 8; and

Fig. 10 is a front elevational view of the studding of Fig. 8.

Referring now to the drawings, there is shown a wall structure adapted for the sub-division of an enclosed building space into a plurality of smaller rooms. The invention finds a particular field of use in the construction of laboratories and similar work spaces which may require rearrangement from time to time and which additionally require numerous service lines such as water, gas, air, vacuum lines and the like, and waste lines for sink and bench drains and, accordingly, the partition will be referred to herein specifically as a "laboratory partition." However, it will be appreciated that it is within the scope of the invention to employ it in the construction of rooms for other purposes where similar problems are involved.

The wall is of unit construction, i. e., it is made of sections of unit size, the unit construction including the arrangement of the plumbing with-

in the wall whereby both the wall units and the plumbing units may be prefabricated and employed in the erection of a partition wall in accordance with any selected plan, the unit construction permitting the later alteration and rearrangement of the partition as may be required.

The unit construction involves the use of a plurality of studs 10 spaced at suitable intervals, preferably 2' intervals, for the length of the wall. The wall surfaces are composed of a plurality of panels of substantially the width of the center to center spacing of the studs, e. g., of a 2' width for 2' stud spacing. The facing panels, indicated generally at 14, are removably secured in place and are divided into vertically adjacent panel sections, as will be hereinafter more fully pointed out. The panels are made of any suitable paneling material but are preferably composed of a hardened, compressed, asbestos-cement material such as "Transite," this material being particularly advantageous for laboratory partitions due to its resistance to corrosion, its easy cleanability, attractive appearance, fire-proofness, and the like.

In accordance with the instant invention the plumbing lines are all concealed within the interior of the wall and are constructed in units correlated to the wall units whereby the partition may be lengthened, shortened or otherwise modified, or the plumbing itself may be modified without difficulty. In the instant case the plumbing lines are shown as made in 4' sections equivalent to the width of two stud spaces, as previously pointed out.

Reference will first be made to the service lines indicated collectively by the reference character 16. Risers 18 leading from mains beneath the floor project into a selected stud space. The lines are connected to the risers through unions 20, L's 21, fittings 22 and connecting nipples. The lines are made up of a plurality of units, unit "A" extending from fittings 22 to the second stud space beyond where they connect into fittings 24. Those lines requiring outlets, an outlet for each of the lines being illustrated, use T fittings which are connected to taps, such as those shown at 28 in Fig. 6, by conventional fittings 26 including nipples extending through openings formed in the wall panel. If outlets from any of the lines are not desired, the corresponding fitting 24 may be a coupling or may be a T with the stem plugged. The pipes of a second unit "B" extend from fittings 24 to the second stud space to the left where they connect into fittings 30. In the construction illustrated, only two of the lines are tapped at this point. For the tapped lines fittings 30 are T's connected to the outlets or faucets 34 through fittings 32. The fittings 30 for the remainder of the lines are couplings or are T's with the stems plugged as previously explained.

As many additional units may be employed as are required to extend the lines the length of, or the desired distance along, the partition wall. Any or all of the lines may be tapped at the junctions of the sections in the manner described above for units "A" and "B."

The lines may also project in the opposite direction from the risers as illustrated by unit "C." The pipe sections making up this unit are connected into fittings 22 and extend to fittings 36 which, as in the case illustrated where the lines are shown ending at this point, may be L's connected to suitable fittings 38 leading to taps

or outlets. As will be appreciated, other fittings may be employed and the line may be further extended if the length of the wall permits. The specific manner in which the units are supported in the wall will be later described.

The waste lines for the several sinks, bench drains, etc. are similarly of unit length, e. g. of 4' length as illustrated in the drawings. Separate waste lines 44 and 46 may be employed, the 10 waste lines extending in opposite directions from the stud spaces adjacent risers 18 to avoid interference with the risers. Referring first to the construction to the left of the risers as shown in Fig. 1, a waste line unit 48 is connected into 15 an L fitting 50 by coupling 52, the L fitting being in communication with a main sewer (not shown) beneath the floor. The fitting preferably has a branch 54, which, in this instance, is capped or otherwise closed off. Unit 48 has a 20 branch 53 coupled at 54 to a drain pipe 56 leading from bench drain 57. A second unit 58 coupled to unit 48 at 60 has a branch 61 coupled at 62 to a drain line 64 from a sink 65. Additional units may be employed to extend the drain line for the 25 full length of or any desired distance along the partition, each of the units carrying a branch or T. These are utilized if a drain is required or are otherwise closed off similarly as in the case of branch 54 of fitting 50. Waste line 46 30 extending to the right of the risers includes unit 66 connected into L fitting 68 through coupling 70. Unit 66 has a branch 71 coupled at 72 to drain line 74 leading from a bench drain 76. A bench drain 77 may drain into L fitting 68 35 through branch 78. All of the units as represented by units 48, 58 and 66 are preferably identical and similarly fittings 50 and 68 are preferably identical in form.

From the above description it will be understood that, as the service lines are made up of 40 connected, similar or identical units, and the drain lines are also made up of connected, similar or identical units, and the partition is likewise of unit construction, two stud spaces being 45 considered a unit, and is of a character to make the lines accessible, the partition may be extended from time to time, or the position of sinks, drains and other equipment along the wall may be changed to meet changing conditions with only minor alterations of the plumbing. For example, sinks may be disconnected from the waste lines and the connections closed. Likewise, closed connections can be opened and connected in with sinks or drains at any time. 50 The tap lines from the service lines may be removed and the fittings plugged, or previously 55 plugged fittings may be connected to taps. Any of the lines may be lengthened or shortened by adding or subtracting units. The construction 60 is entirely flexible. Furthermore, due to the location of all piping within the wall, the entire space up to the wall may be utilized for cabinet or working space (see Figs. 3 and 4). The nipples leading from the service lines to the taps project 65 through the wall rather than through the table as in the conventional case, thus again making more table top space available.

Referring now particularly to Figs. 3 to 7 inclusive, special features of the wall construction 70 which permit the accommodation of the service lines and waste lines within the wall will be described. The studs 10 which support facing panels 14 in the preferred construction include a central core or web 80 (see Figs. 5 to 7) of relatively heavy metal, say, a steel bar $\frac{3}{8}$ " to $\frac{1}{4}$ "

in thickness. The web 80 has a flat transverse forward edge surface 81. Secured to plate 80 are flanged angle members 82 made of relatively light gauge metal, say, 20 gauge steel. Members 82 include face flanges 84 having forward faces 85 lying substantially in the same plane as the forward edge surface 81 of the web 80, integral attachment flanges 86 and integral, retroverted, reinforcing flanges 88. The members are secured to the core plate 80, preferably by welding the attachment flanges 86 to the core plate. Face flanges 84 are provided with means, as indicated at 90, for cooperation with fastening devices carried by surfacing panels 14. The fastening devices may be of any suitable type but preferably for this purpose, fasteners as shown and described in patent to Kellogg, #2,033,100, issued March 3, 1936 are used, as these permit the facing panels to be readily mounted and dismounted from the stud, but hold them firmly and prevent their rattling.

Studs 10 are provided with integral means for supporting service lines 16. The supporting means in the embodiment shown in Figs. 5, 6 and 7 takes the form of recessed seats or notches 92 opening into a face of the stud. Angle members 82 terminate adjacent the notches or seats 92 to leave an uninterrupted opening for lateral insertion of the piping into the seats. Seats 92 are preferably downwardly slanted at a small angle to insure retention of the pipes within the seats, and are made of a width approximately equal to the outer diameter of the pipe to snugly receive the pipes. The seats of the several pipes are closely spaced so that the service lines will be grouped at a single location vertically of the wall.

The several service lines extending to the left from risers 18 are connected into fittings 22 and extend along the wall in unit lengths, as previously described, the lines resting within seats 92 of the studs. As previously mentioned, the units are connected by fittings, such as fittings 24 and 30. Fig. 6 illustrates the manner in which tap lines are taken from the fittings, the tap lines preferably extending through both faces of the wall whereby one series of lines serves laboratories opposite sides of the partition.

The positioning of units C extending to the right of the risers 18 is illustrated in Figs. 2 and 7. The studs in this section of the wall are reversed to place the notches or seats on the opposite face. Unit C of the pipe 16 are mounted in the notches and are connected into the fittings 22 through nipples 98 which cross the stud space. The shifting of units C to the opposite side of the stud space avoids interference between the lines and risers 18.

Referring now to Figs. 8-10 inclusive, a somewhat modified construction of the stud is disclosed. In this embodiment the stud core or web 100 is provided with a single elongated recess or notch 102, indicated by dotted lines in Figs. 8 and 9, the notch being of a length and depth to permit the entire series of lines to extend therethrough. The web 100 has side faces 101 and a transverse forward edge surface 103. An angle plate 104 has a first flange 108 spanning the notch and is secured to the web 100 by suitable means, such as bolts 106, with a second flange 116 extending laterally thereof. The first flange 108 of the angle plate, parallel to the web 100, has a forward edge 107, which should not lie forward of the forward edge surface 103 of the web and preferably, may be substantially flush therewith. A first plurality of notches or seats 110 of the

same shape and character as the seats 92 of the studding shown in Figs. 5, 6 and 7, extend through the forward edge 107 and downwardly and inwardly into the flange 108, the notches having inner terminals 109 and receiving the piping 16 as before.

In this form of the stud means are preferably provided to positively retain the pipes within the seats. For this purpose a retainer strip 112 is placed to overlie the piping and is drawn against it to hold it firmly in position within the seats by bolts or studs 114 passing through perforations in the strip and perforations in the second flange 116 of the angle plate 104.

Referring now to Figs. 3 and 4, the manner in which the waste lines are accommodated within the wall is illustrated. Openings 118 are made in the cores of the studs, the openings extending into the flanges 86 of angle members 82 to the extent necessary to provide an opening of such size as to accommodate the selected diameter of waste lines and to provide the required drainage pitch. The waste lines 44 and 46, as the case may be, are extended through these openings. Inasmuch as, particularly in chemical laboratories, lead lines are required to prevent corrosion by chemicals deposited in the sinks, saddle supports are provided for the lines, as indicated in Figs. 3 and 4, the saddle supports suitably comprising angle members 120 resting on members 122 riveted or bolted to the studs across the opening 118 at variable heights according to the pitch and length of the drain line.

The wall surface is composed of a plurality of panels 14 of substantially the width of the center to center spacing of the studs, the panels being readily removable as previously pointed out. The panel structure for each stud space is made up of a plurality of vertical adjacent panels including preferably an upper panel 124, a lower panel 126, a relatively narrow intermediate panel 128 extending a short distance below the top of the laboratory bench as shown in Fig. 1, and specially mounted access panel 130. The narrow intermediate panel accommodates the nipples for the outlets or taps and the access panels 130 make the service line connections readily accessible. The panels, with the exception of the access panels 130 are secured to the studs by detachable fasteners preferably of the type described in the Kellogg Patent #2,033,100, as referred to above. The access panels are secured in any suitable way that will permit their easy removal. For example, the attachment means illustrated in Fig. 6 comprises straps 132 secured to the back of the access panel and received behind the intermediate panel 128 and catches 134 including cooperating members 136 and 138 carried by the access panel 130 and panel 124 respectively. A knob or knobs 140 may be employed for ease in mounting and removing the panel.

In assembling the wall, the studs are secured to the floor and ceiling or to floor and ceiling runners in the conventional manner and at the proper spacing. The service line units which may be taken from a stock of preformed pieces are mounted in their respective notches or in the angle plates, depending upon the stud design selected, and connected together to form lines, and the lines connected to the risers. The waste line units which similarly may be taken from a stock of preformed pieces are slipped into position within openings 118, and coupled together, the length of the openings permitting the units to be worked into place. These are then connected

with the elbow fittings leading to the sewer and with those elements of the drain fittings located interiorly of the wall. Panels 124, 126 and 128 are assembled on the studs. The various connections may then be made with the taps and with the sink drains.

If for any reason one or more of the service lines must be replaced or changed, or additional lead-offs are required, the access panel may be readily removed and the service lines reached. If the change effects the number of lines extending through the intermediate panel this may be slipped upwardly to disconnect the fasteners of the type shown in the Kellogg Patent #2,033,100 and then removed and a panel of the proper construction substituted. Similarly, drains may be repaired or changed, or additional connections made to the drains by removing the wall panels. No injury to the wall is caused by these alterations, notwithstanding the fact that the lines are all concealed in the interior of the wall. The wall may be lengthened or shortened by adding or removing one or more units made up of the wall panels and studs. The wall is thus susceptible to modification and change to meet changing conditions. Furthermore, it is built from standard parts, preconstructed by factory operations if desired, the erection of the wall being limited to an assembly operation.

Having thus described our invention in rather full detail, it will be understood that these details need not be strictly adhered to and that various changes and modifications may suggest themselves to one skilled in the art, all falling within the scope of the invention as defined by the subjoined claim.

What we claim is:

A wall assembly comprising a plurality of wall panels, access panels, and spaced stud assemblies, each of said stud assemblies comprising an elongated vertically extending web having side faces and a forward edge surface extending transversely thereof and a notch extending inwardly of the web through said forward edge surface, flanged members extending vertically along and secured to said web and terminating adjacent the notch, each of said flanged members having

one flange adjacent a side face of the web and a second flange having a forward face lying substantially in the plane of said forward edge surface of the web and having means removably securing at least one of said wall panels thereto, an angle plate having a first flange attached to a side face of the web and extending vertically therealong and parallel thereto, said first flange of said angle plate spanning said notch and having a forward edge and notches extending through said forward edge and downwardly and inwardly therefrom, the forward edge surface of said web lying at least as far forward as the forward edge of said first flange of said angle plate, said angle plate having a second flange extending laterally of its said first flange rearwardly of the inner terminals of its said notches, a strip, and means removably supporting said strip from said second flange of said angle plate in spaced relationship therewith and substantially parallel thereto along said first flange of said angle plate and transversely of the notches therein and in forwardly spaced relation to the inner terminals of said angle plate notches and rearwardly of said forward edge surface of the web, and means removably securing said access panels opposite said angle plate notches, whereby piping may be supported by said angle plate in said angle plate notches and retained therein by said strip.

EDWARD M. JENKINS.
THOMAS L. ACKEN, JR.
